INVENTOR:

O. O. Price

BY

Norman J. Whittaker
ATTORNEY.

UNITED STATES PATENT OFFICE.

OLIVER O. PRICE, OF OROSI, CALIFORNIA.

ROAD SCRAPER.

1,418,465.

Specification of Letters Patent. Patented June 6, 1922.

Application filed January 26, 1921. Serial No. 440,004.

To all whom it may concern:

Be it known that I, OLIVER O. PRICE, a citizen of the United States, and a resident of Orosi, in the county of Tulare and State 5 of California, have invented a new and useful Road Scraper, of which the following is a specification.

My invention relates to road scrapers or scoops and its principal object is to provide 10 a road scraper or scoop that may be dumped and reset in operative position by the operator of a tractor or other draft means to which the scraper or scoop is attached.

A further object of the invention is to 15 provide a road scraper or scoop having a novel operating means which is within reach of the operator of a tractor to which the scraper or scoop is attached.

Still another object of the invention is to 20 provide a control mechanism for dumping and resetting the scoop or scraper which may be installed on various types of scoops or scrapers.

With the preceding and other objects and 25 advantages in mind that may become apparent from the following disclosure, the invention consists in the novel combination of elements, construction and arrangement of parts and operations to be hereinafter referred to, claimed and illustrated in the accompanying drawings, wherein:

Figure 1 is a side elevation of the invention associated with a tractor;

Figure 2 is a front elevation of the road 30 scraper;

Figure 3 is a top plan view of the same;

Figure 4 is a fragmentary perspective of the control lever embodied in the invention; and

Figure 5 is a detail perspective of the control lever supporting means.

Referring in detail to the drawings wherein similar characters of reference designate similar parts throughout the several views,

the numeral 5 designates a conventional road scraper or scoop provided with a rearwardly extending handle 6 and further provided with side rails or guards 7 which extend parallel to the upper and forward edges of the scoop. A tractor or other draft means is designated at 8 and to which the scoop 5 is attached by means of a clevis 9.

Extending transversely across the scoop 5 at its upper edge and secured to the guards 7 is a horizontal bar 10. Secured to the bar

10 are pairs of spaced uprights 11 provided with registering longitudinally aligned openings 12. Arranged between the pairs of uprights 11 is a vertically adjustable cross piece or fulcrum member 13, the latter being held in adjusted position by means of removable pins 14 passing through the desired openings 12.

A relatively short chain or other flexible element 15 has one end attached to the handle 6 adjacent its inner end while its opposite end is connected with a ring 16 slidably mounted on the handle 6. Resting on the cross piece or fulcrum member 13 is an operating lever 17 which has its forward 60 end disposed in proximity to the tractor 8 so that the operator thereof may grasp the same in order to dump or reset the scraper without dismounting from the tractor. This lever 17 is slidably engaged with the ring 16 and is formed with a vertical extension 18 at its rear end which terminates in a laterally disposed hook 19 that normally overlies and engages the handle 6.

In operation the lever 17 is rotated to disengage the hook 19 from the handle 6. The operator then rocks the lever 17 downwardly which raises the handle 6 to tilt the scoop. Upon raising the control lever the scoop 5 will be set in operative position. The lever 70 is then rotated to dispose the hook 19 over the handle 6 as shown in Figure 1.

It is to be understood that the form of my invention herein shown and described is to be taken as a preferred example of the 80 same, and that various changes in the shape, size and arrangement of parts may be resorted to without departing from the spirit of the invention or the scope of the subjoined claims.

Having thus described my invention, what I claim as new and desire to secure and protect by Letters Patent of the United States, is:

1. The combination with a road scoop and draft means therefor, of a bar extending transversely across the scoop at the upper edge thereof, a dumping and resetting lever resting on the bar and having one end operatively connected with the scoop and its 100 opposite end disposed within reach of the operator of the draft means.

2. The combination with a road scoop having a rearwardly extending handle, a fulcrum bar extending transversely across the 110

scoop at its upper edge, a dumping and resetting lever resting on the fulcrum bar and having one end operatively connected with the handle.

5. 3. The combination with a road scoop provided with a forwardly extending clevis for connection to draft means and a rearwardly extending handle, of a fulcrum bar extending transversely across the scoop at its upper edge, an operating lever resting on the fulcrum bar and having one end operatively connected with the handle.

4. The combination with a road scoop provided with a forwardly extending clevis for connection to draft means and a rearwardly extending handle, of a fulcrum bar extending transversely across the scoop at its upper edge, a flexible element attached to the handle, an element carried by the flexible

element free to slide on the handle, an operating lever resting on the fulcrum bar and having slidable engagement with said slideable element, and a laterally disposed hook carried by the lever and normally engaged with the handle.

5. The combination with a road scoop to be attached to draft means and provided with side rails along its upper and forward edges, and also provided with a rearwardly extending handle, of a cross bar mounted upon the side rails, pairs of spaced uprights secured to the cross bar, a fulcrum bar vertically adjustable between the pairs of uprights, a dumping and resetting lever resting on the fulcrum bar, and operative connections between the operating lever and handle.

OLIVER O. PRICE.
